his Atty.

UNITED STATES PATENT OFFICE.

KURT WANDEL, OF FRANKLIN, MASSACHUSETTS, ASSIGNOR TO SAFEPACK MILLS, OF BOSTON, MASSACHUSETTS, A CORPORATION OF MASSACHUSETTS.

REENFORCED CARTON.

Application filed October 6, 1919. Serial No. 328,845.

To all whom it may concern:

Be it known that I, KURT WANDEL, a citizen of Wurtemberg, and resident of Franklin, county of Norfolk, Commonwealth of Massachusetts, have invented an Improvement in Reenforced Cartons, of which the following description, in connection with the accompanying drawings, is a specification, like characters on the drawings representing like parts in each of the several views.

This invention relates to cartons or boxes produced from a piece of paper or corrugated paper-board or card-board or the like slitted and folded according to common practice to produce a one-piece box, though the invention is not to be understood as necessarily limited to one-piece box constructions. In boxes thus produced from folded paper stock it is well known that the weakest points in the box and where it is most apt to tear or break down are at the folded lateral corners where strains are most apt to be localized and where the fold and crease in the paper stock render it less resistant. The object of the present invention is to provide a box made of paper or paper-board or like stock specially reenforced with strengthening filaments that may be embedded therein and extending around the folded box corners so that these are greatly strengthened and made capable of resisting and withstanding any strains apt to be imposed thereon. The foregoing and other objects and advantages of the invention will more fully appear from the following detailed description, and the distinctive features of novelty will be pointed out in the appended claims.

Referring to the drawings:

Fig. 1 is a plan view showing a blank of paper or paper-board stock formed in readiness for folding to produce a one-piece box and reenforced in accordance with my invention;

Fig. 2 is a perspective view of the box produced in accordance with my invention and illustrating the reinforcing feature;

Fig. 3 is a perspective view illustrating more particularly a manner in which the reinforcing filaments may be applied to the corrugated paper-board stock;

Fig. 4 is a perspective view showing a modified form of the invention; and

Fig. 5 is a perspective view illustrating

more particularly the character of reinforcing means in the form of Fig. 4.

The blank 10 is produced of a single piece of paper or paper-board stock as usual creased or otherwise adapted to be folded along the lines 10^a, 10^b, 10^c to produce the sides of the box and slotted inwardly from the sides thereof as indicated at 10^d, 10^e to produce flaps adapted to be folded in any overlapping relation to form the bottom and top respectively of the box. One end of this blank is shown as equipped with a small projecting flap 10^f adapted for folding over the abutting edge at the other end of the blank when folded thereagainst to secure the box structure together all in accordance with the usual practice. In accordance with my invention reenforcing filaments 11, 12 are applied to the blank 10 running lengthwise thereof and just within the ends of the slits 10^b, 10^e, these filaments in the case of duplex or multiplex paper stocks as commonly employed for making boxes being applied between the layers of the blank and embedded in the adhesive binder thereof. When the box blank thus constituted is folded to produce a box the filaments 11, 12 will thus extend around corners of the box at top and bottom, i. e., at the points where tearing and breaking down of the box is most apt to occur, imparting thus a strengthening and resistant property to the box and making it thus more serviceable. The projecting extremities 11^a, 12^a of the filaments at the ends of the blank may be secured together by tying or otherwise indicated at 13 so that all the corners of the box are correspondingly reenforced. The filaments 11, 12 may be either of metallic wires or of textile threads and they may be located either as indicated just within the extremities of the slits 10^d, 10^e only, or they may be applied throughout the extent of the stock if desired. In Fig. 3 I show a usual form of three-ply paper-board stock 10' adapted for the present purpose, and in this the reenforcing filaments 11 may be embedded between the intermediate corrugated layer and the outer plain layers.

In Figs. 4 and 5 I show a form of the invention wherein instead of the filaments 11, 12, one or more flat thin reenforcing strips which may be of tin-plate or the like may be employed to reinforce the corners of the

- box as described. In this case a three-ply paper stock 100' with a corrugated intermediate layer is shown and between the plies thereof one or more thin flat strips of metal 110 may be applied, there being as shown two of these strips 110 at the top of the box and one such strip 120 at the bottom of the box. The ends of these strips where they come together in overlapping relation may 10 be riveted or otherwise secured together as indicated at 130 so that all the corners of the box are properly reenforced. The reference herein and in the appended claims to paper or paper-board stock as the material 15 of which the box is made is to be understood as only illustrative and intended to typify any suitable sheet stock of which cartons or boxes may be made by folding the same after a manner generally as set forth.
- 20 I am aware that the invention may be embodied in other specific forms without departing from the spirit or essential attributes thereof, and I therefore desire the

present embodiment to be considered in all respects as illustrative and not restrictive, 25 reference being had to the appended claims rather than to the foregoing description to indicate the scope of the invention.

Having described my invention, what I claim as new and desire to secure by Letters 30 Patent is:

A box or carton produced of a single sheet of paper stock slitted on both sides at intervals to produce flaps for folding inward to form the top and bottom of the box, 35 with reinforcing filaments embedded therein extending longwise of the blank and localized directly inward of the inner ends of said slits, the extremities of said filaments projecting from the sheet and securing the 40 abutting edges of the sheet together at the box corner.

In testimony whereof, I have signed my name to this specification.

KURT WANDEL.
